UNITED STATES PATENT OFFICE.

EDSON F. GALLAUDET, OF NORWICH, CONNECTICUT.

AEROPLANE.

1,203,558.

Specification of Letters Patent. Patented Oct. 31, 1916.

Application filed April 4, 1914. Serial No. 829,472.

To all whom it may concern:

Be it known that I, EDSON F. GALLAUDET, a citizen of the United States, and a resident of the town of Norwich, in the county of 5 New London and State of Connecticut, have invented certain new and useful Improvements in Aeroplanes, of which the following is a specification.

This invention relates to flying machines 10 of the aeroplane type, and more particularly to the construction of the outer end portions of the wings or main sustaining planes of such machines.

It has long been known by those skilled 15 in the art of aeronautics that a flying machine provided with dihedral wings and having a low center of gravity will maintain its lateral equilibrium in undisturbed air, but such machines have never come into general 20 use because of the dangerous oscillation to which they are subject when the conditions of the air become much disturbed. It is also well understood that, while the lifting or supporting power of the wings depends 25 mainly upon their surface area and the reaction between the air and their lower surfaces, due both to the angle and velocity of the impact, the moment of inertia of the machine about its fore and aft axis varies 30 according to the square of the distance of the point of the machine from the axis. Consequently, it is a disturbed condition of the air which unbalances the pressure upon the outer ends of the wings, or portions 35 thereof at some distance from the body, which is most dangerous to the lateral stability of the machine. Furthermore, conditions which will have no appreciable effect when the machine is in full flight, both be- 40 cause the rapid motion of the machine tends to raise their rear edges so that the wings will present a smaller angle of incidence and because the inertia due to its momentum gives it steadiness, may overturn the ma- 45 chine or render it very difficult to handle when going slowly, as in starting and alighting.

My present invention consists in a novel construction of the wings in which I utilize 50 these known principles of aeronautics to so balance the tip against the adjacent outer and middle portions of a wing as to substantially neutralize the effect of changes in the air pressure thereon and to automatically

maintain the wings in normal position under 55 varying conditions of flight.

The invention comprises, as its principal feature, a permanent warping of the outer ends of the wings, on opposite sides of the machine, so that their tips will stand at a 60 negative angle of incidence, presenting their upper surfaces to the action of the air, and, secondary thereto, making flexible the upwardly inclined rear sections of the tips and the downwardly inclined rear sections of the 65 adjacent portions of the wings. Thus, the reaction between the air and the tips will tend to depress the outer ends of the wings, and such action upon a relatively small surface at the tips will, because of the long lever arm upon which it acts, substantially 70 counterbalance the disturbing action of the air upon the under side of the adjacent portion of the wings without seriously impairing the lifting or sustaining power of the 75 wings as a whole. And because of their flexibility, the rear sections of the tips and of the adjacent portions of the wings, which when the machine is moving slowly present relatively large angles of incidence, negative 80 and positive respectively, will yield and straighten out so as to present smaller angles of incidence when the machine is moving rapidly through the air.

The invention will be clearly understood 85 from the following description taken in connection with the accompanying drawings, in which—

Figure 1 is a plan view of a novel aero-hydroplane, also of my invention, with a 90 part of the upper surface covering of one wing cut away to show the construction of the outer end portion thereof, in which are embodied the features of the present invention; Fig. 2, a front elevation of the same 95 machine; and Figs. 3 and 4 diagrammatic representations, on an enlarged scale, of the shape of the wing and tip on the section lines 3 3 and 4 4, respectively, of Fig. 1.

Referring to the drawings, the machine 100 there illustrated, by way of example, comprises, as its principal parts, a pisciform body B, provided with the usual fixed tail planes F F', hinged elevating planes E E', and rudder R, and, suitably mounted thereon, the dihedral wings W W', and propellers P P'.

The framework of the wings is formed

with the usual tubular transverse spars 1, 2, and 3 and front and rear edge pieces 4 and 5, which edge pieces are curved, as shown, to give a tapering rearward extension to the outer portions of the wings. The fore and aft ribs 6 of the main portions of the wings, which are suitably mounted upon the spars and connected at their ends to the edge pieces, are curved downwardly at their 10 rear ends, while the rearwardly diverging diagonal ribs 7 of the tips, which are suitably secured to the rear spar and the edge pieces with the outermost rib extending forward and secured to the middle spar to give 15 greater strength, are curved upwardly at their rear or outer ends. The downward curvature of the three or four outer ribs 6 gradually decreases until the outermost of these ribs is substantially straight at its 20 rear end and the upward curvature of the ribs 7, which is small in the case of the innermost rib, reaches a maximum in the two longer middle ribs, and decreases again in the outermost rib; while all of the ribs are 25 tapered from front to rear so as to render them flexible, and more especially so from points in or approximate to the broken line $\alpha\alpha$ (Fig. 1) backward to their extreme rear ends. This framework is covered above and 30 below with the usual or any suitable surface covering 8.

The wing structure thus formed has, on each side of the machine, a permanent warp in its outer end portion which gradually 35 converts the positive angle of incidence of its main portion into a negative angle at the tip, and the rear edge, because of the gradually increasing length of the free tapering ends of the ribs, is increasingly flexible from 40 near the outer end to and at the tip.

The action of the wings in automatically maintaining the lateral stability of the machine will be apparent from the explanation heretofore given. An unbalancing of the 45 air pressure upon the inner portions of the wings on opposite sides of the machine, from the body out to a point indicated by the broken line yy (Fig. 2), for example, has little effect upon the equilibrium of the machine, as already stated, because of the shortness of the leverage relative to the weight and momentum of the machine. The disturbing effect of an unbalanced air pressure upon the wings outside such point is, 50 however, eliminated or reduced to a minimum, since the pressure against the under surface of the wing out to the point indicated by the broken line zz (Fig. 2), where the angle of incidence changes from positive to negative, is counter-balanced by the pressure against the upper surface of the tip, the small area of which is offset by the longer lever arm upon which it acts. Thus, 55 the wings will be held in normal position

and the equilibrium of the machine be maintained however disturbed the condition of the air may be. It is also evident that, because of their relatively small area, the effect of the tips upon the lifting or supporting power of the wings as a whole will be 65 insignificant, and especially so when the machine is in full flight since the tips which normally, and also when the machine is moving slowly and their balancing action is most needed, present larger angles of incidence than the adjacent portions of the wings, will, by reason of the greater flexibility of their ribs, yield more readily and so conform more nearly to the stream lines of the air when the machine is in full flight. 70

75 While I have here illustrated and described my invention as embodied in the dihedral wings of an aero-hydroplane and in the specific form which I now consider to be the best for applying its principle, it is 80 to be understood both that it may be used in flying machines of other types, whether monoplane or multiplane and whatever may be the form of the wings, and that it may be variously modified in its several features 85 and details of construction, within the scope of the appended claims, without departing from the spirit or sacrificing the advantages thereof.

90 What I claim as new, and desire to secure by Letters Patent, is—

95 1. In a flying machine, a rigidly mounted integral wing structure in which the main portions of the wings, on opposite sides of the machine, are concave below and extend outwardly without forward projection at substantially right angles to the fore and aft axis of the machine and near their outer ends are curved rearwardly and permanently warped to provide rearwardly projecting 100 flexible tips, of approximately one-fifth of the length of the wing and of relatively smaller surface area, concave above and yieldingly presenting a negative angle of incidence adapted to automatically counteract unbalanced air pressures upon the under surface of adjacent portions of the wings. 105

110 2. In a flying machine, a rigidly mounted integral wing structure in which the wings, concave below, extend outwardly on opposite sides of the machine without forward projection and substantially at right angles to its fore and aft axis and near their outer ends are curved rearwardly with an increasingly flexible trailing edge and terminate in tapering and rearwardly projecting flexible tips of relatively short length and smaller surface area which, concave above, are permanently but yieldingly flexed to a negative angle of incidence and are entirely automatic in their action. 115

120 3. In a flying machine, a rigidly mounted integral wing structure in which the wings

on opposite sides of the machine, concave below, extend with a slight backward sweep from the body outwardly and near their outer ends are curved rearwardly with an 5 increasingly flexible trailing edge and terminate in tapering and rearwardly projecting flexible tips of relatively short length and smaller surface area which, concave above, are permanently but yieldingly flexed to a 10 negative angle of incidence and are entirely automatic in their action.

4. In a flying machine, a dihedral wing structure in which the rigidly mounted integral wings, set at a dihedral angle, are 15 concave below and extend outwardly and upwardly on opposite sides of the machine at substantially right angles to its fore and aft axis for the main portion of their length and near their integral outer ends are permanently warped to provide flexible tips 20 of relatively short length and relatively smaller surface area concave above and yieldingly presenting a negative angle of incidence.

5. In a flying machine, a dihedral wing structure in which the wings, set at a dihedral angle, are concave below and extend outwardly and upwardly on opposite sides of the machine at substantially right 25 angles to its fore and aft axis for the main portion of their length and near their outer ends are curved rearwardly with an increasingly flexible trailing edge and permanently warped to provide tapering and rearwardly 30 projecting tips of relatively short length and smaller surface area concave above and yieldingly presenting a negative angle of incidence.

6. In a flying machine, a dihedral wing 40 structure in which the lower surfaces of the inner ends of the two wings are extended and joined below the body of the machine to provide a central supporting and planing surface and their outer ends are permanently warped to provide flexible tips of 45 relatively short length and relatively smaller surface area yieldingly presenting a negative angle of incidence.

7. In a flying machine, a dihedral wing 50 structure in which the lower surfaces of the inner ends of the two wings are extended and joined below the body of the machine to provide a central supporting and planing surface and their outer portions are rearwardly curved and terminate in outwardly 55 and rearwardly projecting flexible tips of relatively small surface area permanently but yieldingly warped to a negative angle of incidence and adapted to automatically counteract unbalanced air pressures upon the under surface of adjacent portions of the wings.

8. In a flying machine, a wing structure consisting of a framework and upper and

lower surface covering, the said framework 65 comprising as elements thereof a spar secured to the body of the machine and extending at substantially right angles to its fore and aft axis approximately to the outer end of the wing, front and rear edge pieces, 70 and a series of ribs, mounted upon the spar and connected together at their front and rear ends by the edge pieces, which are convex above and concave below through the main portion of the wing and then gradually 75 change and become concave above and convex below at the tip so as to provide a permanently warped outer portion and a tip of relatively small area presenting a negative angle of incidence. 80

9. In a flying machine, a wing structure consisting of a framework and upper and lower surface covering, the said framework comprising as elements thereof a spar secured to the body of the machine and extending at substantially right angles to its fore and aft axis approximately to the outer end of the wing, front and rear edge pieces 85 flexible at their outer ends, and a series of ribs, mounted on the spar and connected at their front and rear ends by the edge pieces, which near the outer end of the wing are progressively shorter in front and longer and more flexible to the rear of the spar and are shaped and mounted to provide a warped 95 outer portion having a flexible trailing edge and terminating in a rearwardly and outwardly projecting tip normally presenting a negative angle of incidence.

10. In a flying machine, a dihedral wing 100 structure consisting of a framework and upper and lower surface covering, the said framework comprising as elements thereof a spar which is secured to the framework of the machine and extends outwardly therefrom, on opposite sides, at substantially right angles to its fore and aft axis and at an upward inclination approximately to the outer ends of the wings, a series of ribs which are mounted on the spar and are 105 curved and flexible at their rear ends behind the spar, the curvature gradually changing near the outer ends from a downward curvature through the main central portions of the wings to an upward curvature at the 110 tips and the flexibility gradually increasing outwardly toward the tips, and flexible fore and aft edge pieces which respectively connect the front and rear ends of the ribs. 115

11. In a flying machine, a dihedral wing 120 structure consisting of a framework and upper and lower surface covering, the said framework comprising as elements thereof a spar which is secured to the body of the machine and extends outwardly therefrom on 125 opposite sides at substantially right angles to its fore and aft axis and at an upward inclination approximately to the outer ends

of the wings, a series of ribs which through the main central portions of the wings are curved downwardly at their rear ends and near the outer ends of the wings are progressively shorter in front and longer and more flexible to the rear of the spar and have the curvature of their rear ends gradually changed so that it becomes an upward curvature at the tips, and fore and aft edge pieces

which respectively connect the front and rear ends of the ribs, the rear edge pieces being flexible throughout the outer portions of the wings.

EDSON F. GALLAUDET.
